UNITED STATES PATENT OFFICE.

HORACE L. EDGE, OF NEW YORK, N. Y.

GRAIN-STOCKING MACHINE.

1,080,270.

Specification of Letters Patent.

Patented Dec. 2, 1913.

Application filed April 29, 1912. Serial No. 693,986.

To all whom it may concern:

Be it known that I, HORACE L. EDGE, a citizen of the United States, and resident of New York city, borough of Brooklyn, in the county of Kings and State of New York, have invented certain new and useful Improvements in Grain-Stooking Machines, of which the following is a specification.

My invention relates to improvements in machines for stooking or shocking sheaves of grain, and has for its object to receive, as from a grain binder, the required number of sheaves for a stook or shock, deposit them upon the ground at the rear of the machine, and then release the stocks or shocks.

Grain binders usually deliver the sheaves of grain with their butt-ends extending forwardly of the machine, and my improvements are designed to receive the sheaves from the binder in suitable arms or a basket with the butt-ends of the sheaves extending forwardly, cause the arms to clamp the required number of sheaves for the stook, swing such arms and sheaves around end for end, deposit the stook upon the ground, and release the arms from the stook, the arms or basket then returning to the normal position ready to receive the next supply of sheaves, and so on.

My invention comprises novel details of improvement and combinations of parts that will be more fully hereinafter set forth and then pointed out in the claims.

Reference is to be had to the accompanying drawings forming part hereof, wherein,

Figure 1 is a rear elevation of a stooking or shocking machine embodying my invention; Fig. 1^a is a plan view of part thereof showing the parts in the sheaf-receiving position; Fig. 2 is a plan view, illustrating the parts in position about ready to deposit a stook upon the ground; Fig. 3 is a partly sectional plan view, showing the parts in the stook receiving position; Fig. 4 is a vertical section on the line 4, 4, in Fig. 3, looking in the direction of the arrows, but illustrating the parts in the position for the stook-holding arms to deposit the stook; Fig. 4^a is a detail of devices for causing the mechanism to return sheaf or stook receiving arms or basket to normal from the position shown in dotted lines in Fig. 4; Fig. 5 is a partly sectional front elevation of the machine, showing the sheaf or stook receiving arms in position to receive the

sheaves; Fig. 6 is a sectional detail of clutch mechanism on the main shaft; Fig. 7 is a section on the line 7, 7, in Fig. 6; looking in the direction of the arrows; Fig. 8 is a front elevation of the machine showing the 60 stook-receiving arms closed; Fig. 9 is a partly sectional plan view of part of the machine, showing the parts in the normal or stooking position; Fig. 10 is a detail section on the line 10, 10 in Fig. 9; Fig. 11 is 65 a detail section of the arm 91 and its projection 93; Fig. 12 is a detail face view of the latter; Fig. 13 is an enlarged view, partly in section, looking from the lefthand side of Fig. 8, and Fig. 14 is a detail section; 70 substantially on the line 4, 4, in Fig. 3, looking in the reverse direction of the arrows.

Similar numerals of reference indicate corresponding parts in the several views.

The numeral 1 indicates a suitable frame 75 shown having a table or platform 1^a, upon which the mechanism hereinafter described is mounted, the frame being shown in skeleton form for lightness of construction. Frame 1 is provided at its outer side or end 80 with a wheel 2 to run upon the ground, and at the opposite side said frame is adapted to be connected with the frame 3 of a binder of any well known construction, shown provided with the customary chute 4 for delivering the bound sheaves of grain to the conveyer or elevator 5 carried by frame 1 (see Fig. 1).

Conveyer 5 may be of any suitable or well known construction, and may comprise 90 the endless belt 6 having the fingers 7 to carry up the sheaves and deposit them in the arms, or a basket 8, to form the stocks. The arms 8 are shown of substantially semi-circular form, pivoted together at their 95 lower ends upon a pivot 9, carried by a swinging arm or plate 10 journaled at 11 upon a turntable or rotatable frame 12 mounted upon plate 1^a. The arms 8 are adapted to be spread apart (Fig. 1) to receive the sheaves from the elevator, and to be closed to grip the sheaves (Figs. 2 and 8). The arms 8 are shown provided with suitable plates 8^a (Figs. 1, 1^a and 4) disposed transversely of the arms to balance 100 the sheaves of grain. A plate 8^b may be placed loosely over the joint of arms 8 (Fig. 5) to keep the sheaves from entering such joint. The arms 8 are normally spread 105 apart to receive the sheaves, and means are 110

provided to close the arms upon the desired number of sheaves, swing the arms around toward the back of the machine, lower the arms with their contained stock upon the ground, and open the arms to release the stock (ready to receive further sheaves) and restore the arms to the sheaf or stock receiving position. I have shown a spring 13 connecting the lower projections 8^c of arms 8 (Figs. 5 and 8), tending normally to spread the arms apart. To close arms 8 upon the sheaves the telescopic rods 14 are pivotally connected with projections 8^c, as at 15, and are pivotally connected 10 with a stud 16 shown connected with a block 17 guided in a slot or fork 18 of or secured on plate 10, a spring 19 upon one or both the rods 14 serving to press such telescopic rod lengthwise (see Figs. 5 and 8). 15 To close the arms as required (that is to say, when the desired number of sheaves are in the arms) I provide a cam 20 (Figs. 1, 2, 8 and 13) adapted to coact with stud 16 to raise the latter, which stud may have a roller 16^a (Fig. 13) to engage the cam. 20 Cam 20 is carried by a shaft 21 having a gear 22, meshing with a gear 23 on a shaft 24 to be driven intermittently (Figs. 2, 3, 8 and 13), whereby said cam may engage 25 and raise stud 16, and thereby raise arms 14 and spread them to cause spreading of projections 8^c and closing of arms 8, as in Fig. 8, whereupon the arms will remain in the position shown, (due to the then angular relation of the parts and block 17 engaging the top of slot 18) until stud 16 is pulled down to cause arms 8 to spread apart, as hereinafter shown. Shaft 24 may be caused 30 to rotate at the required time by the operator releasing a clutch, that controls the shaft, for releasing the shaft from the operation of its drive gear 25, which is loosely mounted upon said shaft. Gear 25 is shown meshing with gear 26 secured on drive 35 shaft 27 (Figs. 2, 3, 4, 6, 7 and 14). The shaft 27 may be the main driving shaft, and may receive its motion from a shaft of the binder, or may be driven in any other suitable manner, gear 26 being thus continuously driven and correspondingly driving the gear 25. Shaft 27 carries a loose sleeve 28 for operating a cam 29 at the desired time, as hereinafter explained (Figs. 2, 3, 6, 8, and 14). Clutch devices are provided 40 for connecting shaft 24 with wheel 25, and shaft 27 with sleeve 28, at the desired times. The clutch mechanism I have shown for each of such purposes is similar, and the description of one clutch mechanism will 45 suffice, corresponding reference numerals relating to both, since any suitable clutch mechanism may be used. The clutch mechanism is more fully shown in Figs. 4, 6, 7 and 14, and comprises a drum 30 having 50 a peripheral groove 30^a, and a recess 30^b

receiving a beveled extension 31 on a bolt 32 (Figs. 6 and 7) adapted to pass through a hole 33 in the drum and to engage arms or abutments 34 on wheels 25 and 26. The opposite ends of bolts 32 receive springs 35 shown inclosed by caps 36 serving normally to press bolts 32 toward wheels 25 and 26, (Fig. 6). The drums also have stop pins 37. To control the clutch of shaft 24 lever 38 is provided (Figs. 4, 7 and 14) and has 75 a pin 39 (Fig. 7) to engage pin 37 to check the adjacent drum 30 in the normal position. Lever 38 also has an inclined face 38^b (Fig. 14) to engage the inclined portion of the projection 31 to release bolt 32 from wheel 25. Lever 38 is shown in Fig. 7 in the releasing position, and a portion of the lever normally rides in the groove 30^a of drum 30. Lever 38 may be held in the normal position by a spring 40, and may 80 be operated by a rod 41 (Figs. 1, 3, 4, 7 and 8). In the normal position of lever 38 its inclined face 38^b will engage projection 31 of bolt 32 and withdraw the bolt from wheel 25, and pin 37 will engage pin 39 to stop drum 30 at normal, and when said lever is rocked by lifting rod 41 pin 37 and bolt 32 are released and bolt 32 immediately engages with wheel 25 to cause a complete rotation of shaft 24, and then 90 the clutch is released by inclined face 38^b engaging projection 31 and withdrawing bolt 32, pin 37 then engaging pin 39, and the shaft stops, at which time cam 20 has been rotated to close arms 8. A lever 42 100 is arranged similarly to lever 38 in connection with drum 30 of shaft 27, but over the drum (Figs. 2, 3, 4, 6, 14), which lever 42 has a pin 42^a and an inclined face 42^b to engage the inclined portion of projection 105 31 of the corresponding bolt 32 (Fig. 6). Lever 42 is carried by a shaft 43 for rocking said lever at a time to be described hereinafter. The arrangement is such that when pin 42^a engages pin 37 of the clutch 110 drum shaft 27, the inclined face 42^b will engage the inclined portion of projection 31 and withdraw the bolt 32 from wheel 26, and cam 29 will then be held in the normal position by reason of the connection 115 of the corresponding drum with sleeve 28. When, however, lever 42 is raised bolt 32 and pin 37 are released and bolt 32 immediately engages wheel 26, and its drum 30 is rotated one rotation to correspondingly rotate cam 29, and at the termination of such rotation bolt 32 is withdrawn from wheel 34, and pins 37 and 42^a engage and 120 retain cam 29 in normal position.

Rod 41 will be raised by the attendant at 125 such time as the desired number of sheaves are in arms 8, and at that time conveyer or elevator 6 may be stopped until arms 8 have deposited the contained stock and returned to the sheaf or stock-receiving posi- 130

tion. For this purpose I have shown a clutch 43 to control the operation of drive shaft 44 of conveyer 6, the lever 43^a of which clutch is shown operatively connected with 5 rod 41, Fig. 1. Shaft 44 is shown provided with a gear 44^a meshing with a gear 6^a of the drive shaft of conveyer, apron or belt 6, and the short shaft 45 is shown provided with a gear 45^a meshing with a gear 46 secured on shaft 47. Gear 46, is thus connected to a sprocket 47^a secured on said shaft and receiving a chain 48 from a drive sprocket 49 on shaft 27 (Figs. 1, 2, 3, 8 and 14). The arrangement is such that when 10 rod 41 is raised to cause the corresponding clutch mechanism to operate shaft 24 and cam 20, the clutch 43 will be released and shaft 44 will stop, and the conveyer will cease delivering sheaves, and when the corresponding clutch mechanism of shaft 24 15 returns to its normal position, clutch 43 will reengage causing the conveyer again to deliver sheaves to arms 8, and so on.

To aid in retaining the sheaves in arms 8 20 while the arms are expanded, I provide a stop or abutment 50, which is held in such position, when the sheaves are being delivered to arms 8, as to engage the butts of the sheaves. The stop or abutment 50 is 25 shown in the form of a wall or housing having sides 50^a and an open top, the lower front portions of the sides 50^a being cut away at 50^b (Fig. 4) to permit free passage of the plates 8^a as the latter swing away 30 from the sheaf-receiving position. The stop or abutment 50 is shown carried by arms 51 35 pivotally supported upon plate 1^a and adapted to be held forwardly and released as required (Figs. 1, 4). One of the arms 40 51 is shown connected by a link 52 with a rock arm 53 controlled by cam 29 (Figs. 1, 4 and 5). Link 52 is shown provided with a notch 52^a (Fig. 4) adapted to receive projection 54 (see dotted lines in Fig. 4) on a 45 rock arm 55 pivotally supported upon bracket b, as at 56, (Fig. 4). Rock arm 55 is pivotally connected with a bar 57, the lower end of which is forked to straddle and be guided by shaft 24 (Fig. 4). Bar 57 is 50 provided with a projection 57^a to be engaged and lifted by a cam 58 on shaft 24 55 (Figs. 2, 4 and 8). The arrangement is such that when arms 8 are spread apart in the normal position, cam 29, by having moved in the direction of its arrow in Fig. 4, will have swung arm 53 to the right and drawn stop or abutment 50 rearwardly, by 60 pulling on link 52 and arm 51, and notch 52^a will have engaged projection 54, but when shaft 24 is rotated to cause cam 20 to close arms 8 bar 57 will have been raised by cam 58 to cause projection 54 to release arm 52 and thereupon stop 50 will automatically swing outwardly away from the 65 sheaves in the arms 8. The time of opera-

tion of cam 29 for the purpose above set forth will be explained hereinafter. A link 59 pivotally supported at 59^a and movably connected with stop 50, has stops or nuts 59^b, 59^c, to co-act with a guide 50^a of stop 50 (Figs. 2 and 4) to retain stop 50 in the outward and inward positions.

The arrangements for swinging the arms 8 from the sheaf receiving position, after the arms have grasped the stock, to the stock delivering position at the rear of the frame, and for causing the stock to be deposited upon the ground, and the arms restored to the sheaf receiving position, are as follows: The shaft 47 is shown connected by a universal joint 60 with a shaft 61 upon which is slidably mounted a sleeve 62 having a disk 62^a, upon which sleeve is loosely mounted a bevel gear 63, and upon which shaft is loosely mounted a bevel gear 64 (see Figs. 1, 9 and 10). The ends of shaft 61 and sleeve 62, adjacent to gears 63 and 64, are journaled in a suitable bracket 65 that is guided by a shaft 66 secured to turntable 12 (Figs. 10, 13), whereby the turntable may revolve freely with respect to bracket 65. Between and meshing with gears 63, 64, is a bevel gear 67, suitably secured to shaft 66, as by screw 68 (Fig. 10), whereby gear 67 will rotate shaft 66 and turn table 12. The inner faces of gears 63, 64 are respectively provided with clutch members 63^a, 64^a, adapted to be engaged by the complementary clutch members 69^a, 69^b of clutch block 69 that is secured upon sleeve 62 and slideable along shaft 61 to rotate with said shaft, as by the screw or key 70 passing from block 69 into the groove or keyway 61^a of shaft 61 (Figs. 1, 9 and 10) whereby gears 63 and 64 may be caused to rotate gear 67 and the turntable 90 in opposite directions as required. Sleeve 62 is to be shifted longitudinally to cause engagement of clutch members 63^a, 69^a or 95 64^a, 69^b as required, and for this purpose I have shown a fork member 71 engaging disk 62^a and connected or formed with an arm 72 for rocking said fork (Figs. 8, 9), which fork and arm are in the nature of a bell-crank lever pivotally supported upon bracket b on table 1^a, (Figs. 1, 2, 4, 8, 9 and 13), and block 69 will be held in a neutral position, with the clutch members disengaged, when the turn table is not being rotated, as when the turn-table and arms are in the sheaf-receiving position (Figs. 1, 8, 120 9 and dotted lines in Fig. 4), and in the sheaf-delivering position (Figs. 2 and 5, and full lines in Fig. 4). Arm 72 is automatically shifted to the various positions required by and during the rotation of the 125 turntable. When arms 8 of the turntable are in the sheaf-receiving position, arm 72, being in the neutral position, rests against an inclined abutment 73 on the turntable (Figs. 3 and 9). To shift arm 72 when the 130

sheaf binding arms 8 are closed upon the stool, I connect arm 55, by a link 74, with a bell-crank lever or rock arm 75, the upper arm of which is pivotally connected at 76 with arm 72 (Figs. 2, 4 and 8), lever 75 being pivotally connected at 75^a with bracket b (Fig. 4). The arrangement is such that at the termination of the rotation of cam 20 to close arms 8, cam 58 of shaft 24 will have 10 raised bar 57 and thereby, through link 74 and rocker 75, will have shifted arm 72, which, acting upon disk 62^a, will have slid sleeve 62 to place clutch members 63^a, 69^a into engagement to thereby cause gear 63 15 to rotate gear 67 and the turntable one-half rotation, swinging arms 8 and the stool grasped thereby around, end for end, with the butts of the sheaves toward the back of the machine. At the termination of such 20 stroke an abutment 77 upon the turn table (Figs. 1, 2 and 9) will have engaged arm 72 (Fig. 2) and shifted it back to the neutral position, to disengage the clutch members. To normally retain the arms 8 and the stool 25 grasped thereby in the elevated sheaf-receiving position, and to cause said arms and stool to swing down behind the machine to deposit a stool upon the ground, I provide the following arrangement: The arm or plate 30 10 and the arms 8 are normally held upright by a latch or catch 78 (Figs. 2, 4, 4^a, 8, 9, 13) normally engaging a stop 79 on the turntable and held down on said stop by a spring 80 (Figs. 3, 4, 13). Latch 78 has a 35 side projection 78^a provided with an inclined under face 78^b (Figs. 1, 3, 4, 4^a, 8, 9, 13), adapted when arms 8 and turntable 12 about meet their extreme rotary movement to the rear of the machine, to engage a projection 40 81 of a lever 82, pivoted at 82^a upon bracket b (Figs. 1, 2, 3, 4, 4^a, 8, 13) lever 82 being held in normal position by spring 83 drawing the lever against stop 84 (Fig. 3). When the inclined edge 78^b of projection 78^a 45 of latch 78 engages projection 81, the latch is raised and releases arm or plate 10, whereupon the weight of the stool causes arms 8 to swing down and deposit the stool upon the ground. The arms will then be opened 50 and release the stool, as hereinafter explained, and the springs 10^a, that connect plate 10 with bracket c on the turn table (Figs. 1, 1^a, 3, 4), swing plate 10 and arms 8 upwardly to the normal position, said arms 55 remaining separated. As the projection 78^a of latch 78 now approaches the outer end of pin 81 it will engage said pin and shift lever 82 toward arm 72 (the latch meanwhile riding up upon stop 79) and engaging the latter to again hold plate 10 and arms 8 in the 60 normal positions.

The shifting of arm 82 as just stated causes a projection 82^b of said arm (Figs. 2, 3, 4, 4^a, 13) to engage arm 72 and rock it 65 to cause disk 62^a and sleeve 62 to shift the clutch block or member 69 to the right in Fig. 10, to engage the clutch members 64^a, 69^b, and thereby, by the rotation of shaft 61, cause gears 64 and 67 to rotate turntable and arms 8 reversely, to their normal positions. At about the termination of such rotation of the turntable the incline 73, engaging the roller at the end of arm 72, shifts the latter back to neutral, thus causing disengagement of the clutch members 64^a, 69^b, retaining again the clutch member 69 in neutral (Fig. 10). The turntable 12 may be caused to remain set in the sheaf-receiving and in the stool-depositing positions, by means of a pin 85 pressed by a spring 85^a into sockets or recesses 85^b at diametrically opposed positions upon slide or base plate 12^a of the turntable (see Fig. 13). Spring 85^a is shown 80 enclosed in a housing 85^c against which said spring bears, said spring also bearing against a projection 85^d of pin 85. The lower end of pin 85 may be shaped to permit its ready rising from recess 85^b when rotation of the turntable is started.

As has been stated, when arms 8 swing 90 down to deposit the stool upon the ground they are to be opened to release the stool, and it is also the object of my invention to cause the arms carrying the stool to move relatively to the main frame, or as may be 95 said, when the stool rests upon the ground, held by arms 8, the machine may advance with respect to the turntable and stool while the arms 8 are being spread apart, not to drag the stool along the ground. This I 100 accomplish by mounting the turntable 12 so as to slide upon the frame in a rearward direction. I have shown positive means for causing the turntable to so slide rearwardly, and a spring to draw the turntable back to 105 normal position. The turntable 12 is pivotally supported upon slide 12^a as by ball or roller bearings, and said slide 12^a is mounted in suitable guideways 86 on table 1^a to slide fore and aft of the machine, and at the forward end of the slide a rack 87 is secured and guided to slide in suitable bearings 88 (Figs. 2, 3, 5, 8) secured upon plate 1^a. A partial gear 89 is adapted to mesh with rack 87 and be free therefrom as required, which 110 gear is secured upon a shaft 90 journaled in suitable bearings upon plate 1^a. Shaft 90 is provided with a sprocket wheel 90^a receiving a drive chain 90^b from a sprocket wheel 2^a secured on wheel 2. A clutch 115 mechanism is provided to cause shaft 90 to rotate gear 89 intermittently as required, which clutch mechanism may be similar to that described with respect to the clutch mechanisms of shafts 24 and 27, the bolt 32 of drum 30 being adapted to rotate the gear 89 (Fig. 8). A lever 91, pivotally supported at 92 and normally held down by a spring 91^b (Figs. 1, 2, 3 and 8) is provided 120 with an inclined face 91^a (Fig. 8) to release 125

bolt 32 from gear 89. Lever 91 is provided with an inward projection 93 having inclined under face 93^a (Figs. 2, 3, 11 and 12) adapted to be engaged by a pin 94 carried by turntable 12 (Figs. 1, 2, 3, 5, 9) which pin 94 is normally in the position shown in Fig. 3, but as the turntable is swung around to present the arms 8 at the rear of the machine, the pin 94 by engaging projection 93, 10 will lift lever 91 and release it from the corresponding clutch bolt 32, whereupon the latter will engage gear 89 and connect it with shaft 90. As shaft 90 is continuously rotated from the ground wheel 2, gear 89 15 will thereupon be caused to engage rack 87 and thereby push said rack, slide 12^a and the turntable, with the stock carried by arms 8, to the rear of the machine. This sliding movement of the turntable takes place at 20 about the time the turntable reaches its rearward stopping position, and thereupon the weight of the stock will cause arms 8 to drop down and the stock will rest upon the ground. When arms 8 swing down the stud 25 16 swings down in line with an abutment or yoke 95, shown carried upon guides 86, (in the path of stud 16) and as slide 12^a continues to move rearwardly with respect to the machine, at substantially the speed of 30 the machine, the stock will remain upon the ground in a substantially permanent position, and stud 16, by engaging abutment 95, will be pushed back along the slot 18, causing arms 8 to open and release the stock. 35 As soon as the teeth of gear 89 pass from the rack the latter is released and the springs 96 connecting plate 1^a with slide 12^a pull the slide and turntable back to the normal positions, and as the arms 8 are now released 40 from the weight of the stock said arms will be raised by springs 10^a as before described. The pin 94 is spring pressed outwardly so that on the return rotation of turntable 12 the pin will slide back by encountering projection 93, but without raising lever 91. 45 When lever 91 has been released by pin 94 on the first rotation of the turntable from normal, said lever is restored to its normal position to pull the corresponding clutch bolt 32 away from gear 89 upon the termination of one rotation of shaft 90 in the manner explained hereinbefore, so that the operation of slide 12^a shall be intermittent. 50 The pin 94, in returning to the normal position, engages an arm 43^a secured on shaft 43 (Figs. 1, 3, 4, 5) whereby when the turntable returns to normal to receive sheaves said pin 94 raises arm 43^a and rocks shaft 43, and thereby raises arm 42 from the corresponding clutch releasing pins of the latter to cause engagement of the bolt 32 and gear 26, to then cause operation of cam 29, 60 whereby the latter then raises the stop or abutment 50 to the normal active position, in manner before described, as shown in dotted 65 lines in Fig. 4. A spring 42^c connecting arm 42 with bracket *b*, restores said arm to its normal position, Figs. 5 and 8.

The complete operation may be described as follows: The machine being attached to a binder, and shaft 27 connected to a driving member for continuous rotation during work, the turntable will be set in the normal position, with arms 8 spread apart, to act as a receiver or holder for the sheaves delivered to the machine from the binder; and stop 50 will have been drawn up by the action of cam 29 and retained, as in dotted lines in Fig. 4, by projection 54 engaging notch 52^a of rod 52. Clutch 43 now being set, the conveyer or elevator then delivers the sheaves, over the top of arms 8, which drop into the latter, the machine being moved along the ground and wheel 2 rotating continuously. When the operator sees that the desired number of sheaves are in receiver-arms 8 he raises rod 41, whereupon the elevator stops and lever 38 is depressed to cause the clutch mechanism of shaft 24 to connect the latter with its driving wheel 25, and thereupon cam 20 is rotated in the direction of the arrow in Fig. 8, and by engaging stud 16 (which will then be in the lowered position Fig. 5) arms 8 will be closed upon the sheaves therein and the stock formed. When arms 8 have grasped the stock the cam 58 will have raised bar 57 and elevated projection 54 from notch 52^a and released link 52, whereupon stop 50 will swing away from the stock, and the continued rise of bar 57 will have operated rocker or bell-crank 75 sufficiently far to cause arm 72 to shift clutch member 69^a into engagement with clutch member 63^a, and thereupon gears 63 and 67 will cause the turntable to rotate in the direction of the arrow in Fig. 3, with the stock supported by arms 8. The butts of the stock will then be reversed in position with respect to the travel of the machine. When the turntable about reaches the limit of its rotation, projection 77 will engage arm 72 (Fig. 2) to cause clutch member 69 to be shifted to neutral to release the turntable rotating gears, the latch projection 78^a by riding upon pin 81 releases arm or plate 10, the weight of the stock swings arms 8 and plate 10 downwardly, so that the stock can rest upon the ground, and pin 94 will have operated lever 91 to cause the corresponding clutch mechanism to connect shaft 90 with gear 89, and the rotation of said gear, by the connection of the same with the road wheel, will cause relative movement between slide 12^a and the machine, and the rearward movement of the turntable thus caused enables stud 16 to encounter abutment 95 to cause arms 8 to open and release the stock, yet, while said arms are opening, the stock will stand still on the ground because the 130

turntable slides rearwardly upon or with respect to the forwardly moving machine frame. The release of the weight of the stuck from arms 8 permits them to be raised by springs 10^a to their normal upright and expanded position, while the release of gear 89 from rack 87 permits springs 96 to pull the turntable back to its normal position on slide 12^a. As plate 10 rises the projection 78^a of rod 78 encounters the end of pin 81 and swings arm 82 (upwardly in Fig. 2) causing the projection 82^b to shift arm 72 to cause engagement of clutch members 69^b, 64^a, and latch 78 engages stop 79 to hold the now spread arms in normal elevated positions upon the turntable; the rotation of shaft 61 through the gears 64, 67 now will cause the turntable to rotate to return to normal, and thereupon the inclined face 73 engaging arm 72 will cause the latter to shift clutch member 69 to neutral and release the associate gears. At about the termination of the return rotation of the turntable the pin 94, by engaging arm 43^a, raises the latter causing shaft 43 to rock and raise arm 42 to release the corresponding clutch bolt 32, which thereupon engages wheel 26 connecting the latter operatively with sleeve 28, and thereupon cam 29 is rotated against arm 53 to rock the latter, thereupon link 52 is pulled to raise stop 50 into position respecting arms 8, and projection 54 enters notch 52^a to retain said stop in set position (see dotted lines in Fig. 4); said clutch bolt 32 then by engaging incline 42^b of lever or arm 42 is withdrawn from wheel 26, cam 29 comes to rest, and the parts are all then restored to their normal positions ready to receive further sheaves. The attendant then operates clutch 43 to cause the elevator or conveyer to again deliver sheaves to arms 8, and the operations are repeated.

From what has been described, it will be understood that by attaching my improved machine to a binder the sheaves of wheat, as delivered from the binder, may be formed into stucks in the receiver or arms 8 with their butts projecting forwardly in the direction of travel as delivered from the binder; that said stuck will be swung around bodily with its butts to the rear of the machine, then swung down and rested upon the ground and released from the receiver arms, all without requiring any handling by the operator, without unduly shaking the grain, and without dragging the stuck along the ground, and while the binder is binding the sheaves and delivering them to my improved stocking or shocking machine.

While I have illustrated and described a practical form of my invention, it will be understood that the same is not limited to the particular details of construction and arrangements of parts set forth, but that the same may be varied, within the scope of the

appended claims, without departing from the spirit of my invention.

Having now described my invention what I claim is:

1. A stooking machine comprising a sheaf receiver having relatively movable arms, a cam located below said receiver arms, means between the cam and arms to cause the latter to close upon sheaves, means to move said receiver from the sheaf receiving position to the sheaf delivering position, means to rotate said cam and means to cause said receiver to deposit the sheaves upon the ground and release said sheaves. 70

2. A stooking machine comprising a rotative sheaf receiver having relatively movable arms, a cam located below said receiver arms, means connected with said arms and actuated by said cam to cause said arms to close upon sheaves, means for rotating said receiver from the sheaf receiving to the sheaf delivering position, means to rotate said cam intermittently, means to cause the receiver to deposit and release said sheaves, and means to restore said receiver to the sheaf receiving position. 80

3. A stooking machine comprising a receiver having relatively movable arms to receive and hold sheaves, a cam, means connected with said arms and co-active with said cam to cause said arms to close upon sheaves, said arms being supported to move from an upward sheaf receiving position to a lowered sheaf depositing position, means to actuate said cam, means to rotate said receiver from the sheaf receiving position, means to cause lowering of said receiver to the sheaf depositing position, and means to release said receiver from said sheaves. 95

4. A stooking machine comprising a receiver having pivotally supported arms to receive and hold sheaves, a cam located below said arms, the latter having movable members co-active with said cam to cause said arms to close upon contained sheaves, 110 means to rotate said cam, said arms being supported to move from an upward sheaf receiving position to a lowered sheaf depositing position, means to cause lowering of said receiver to sheaf depositing position, and 115 means to spread said arms apart in the last named position to release the contained sheaves. 105

5. A stooking machine comprising a receiver having a pair of relatively movable upwardly extending arms to receive sheaves between them, a cam pivotally supported below said arms, a stud connected with said arms and co-active with said cam to cause said arms to close upon the sheaves, a pivotally supported plate carrying said arms, said plate and arms being movably supported to swing to turn the contained sheaves around end for end, means to cause said arms to swing downwardly when turned from the 120 125 130

sheaf receiving position, and means to spread said arms apart to release the sheaves.

6. A stooking machine comprising a receiver having relatively movable arms to receive and hold sheaves, a plate pivotally carrying said arms, a rotative support to which said plate is pivotally connected for said plate and arms, means to cause said arms to close upon contained sheaves, means to cause said support to rotate upon the closing of said arms to the sheaf depositing position, means to allow said plate and arms to swing down in the last named position, and means to cause said arms to open upon reaching said position.

7. A stooking machine comprising a receiver having relatively movable arms to receive and hold sheaves, a rotative support for said arms, a cam below said arms, rods connected with said arms, means to operate the rods by the cam, to cause said arms to close upon contained sheaves, means to cause said support to rotate upon the closing of said arms to the sheaf depositing position, means to cause said arms to swing downwardly, and means to cause said arms to release said sheaves when in the last named position.

8. A stooking machine comprising a receiver having pivotally supported arms to receive and hold sheaves, a rotary support carrying said arms, a cam, mechanism to operate the cam to close said arms upon the sheaves, mechanism to rotate said support, means operated with the cam operating mechanism to cause the support-operating mechanism to rotate the latter upon closing said arms, means to stop rotation of said support in the sheaf depositing position, and means to cause said arms to deliver the sheaves in the last named position.

9. A stooking machine comprising a receiver having pivotally supported arms to receive and hold sheaves, a rotary support carrying said arms, a cam, mechanism to operate the cam to close said arms upon the sheaves, mechanism to rotate said support, means operated with the cam operating mechanism to cause the support-operating mechanism to rotate the latter upon closing said arms, means to stop rotation of said support in the sheaf depositing position, means to cause said arms to swing relatively to said support to deposit the sheaves, and means to cause said arms to release the sheaves when in the last named position.

10. A stooking machine comprising a receiver having pivotally supported arms to receive and hold sheaves, a rotary support carrying said arms, a cam, mechanism to operate the cam to close said arms upon the sheaves, mechanism to rotate said support, means operated with the cam operating mechanism to cause the support-operating mechanism to rotate the latter upon closing

said arms, means to stop rotation of said support in the sheaf depositing position, means to cause said arms to deposit the sheaves in the last named position, and means to cause said support and arms to swing back to the sheaf receiving position.

11. A stooking machine comprising a receiver having pivotally supported arms to receive and hold sheaves, a rotary support carrying said arms, a cam, mechanism to operate the cam to close said arms upon the sheaves, mechanism to operate said support, means operated with the cam operating mechanism to cause the support-operating mechanism to rotate the latter upon closing said arms, means to stop rotation of said support in the sheaf depositing position, means to cause said arms to swing relatively to said support to deposit the sheaves, means to cause said arms to release the sheaves when in the last named position, means to raise said arms when the sheaves are released therefrom, and means operated upon the rising of said arms to cause the support-operating mechanism to rotate the latter back to the normal sheaf receiving position.

12. A stooking machine comprising a rotative support, a pair of relatively movable arms carried by said support to receive sheaves, a movable member connected with said arms to close the same, a cam to operate said member, driving mechanism to operate said cam, devices for rotating said support including clutch mechanism, means operated with the cam-operating mechanism to shift the clutch mechanism to cause said devices to rotate said support to the sheaf depositing position upon the closing of said arms, means to cause said arms to open to release the sheaves, and means to cause said clutch mechanism to shift to cause said devices to rotate the support back to the normal position.

13. A stooking machine comprising a rotative support, a pair of relatively movable arms carried by said support to receive sheaves, a movable member connected with said arms to close the same, a cam to operate said member, driving mechanism to operate said cam, devices for rotating said support including clutch mechanism, means operated with the cam operating mechanism to shift the clutch mechanism to cause said devices to rotate said support to the sheaf depositing position upon the closing of said arms, means to cause the arms to swing down to deliver the sheaves, means to cause the arms to open to release the sheaves, means to cause the arms to rise from the sheaves, and means operated upon the rising of said arms to shift the clutch mechanism to cause said devices to rotate the support and arms back to the normal position.

14. A stooking machine comprising a rotative support, a plate movably carried

thereby to swing up and down, arms movably carried by said plate, means to retain the plate in connection with said support, means to close the arms upon contained 5 sheaves, means to rotate said support and arms with the sheaves to the sheaf-depositing position, means to release the plate upon reaching the last named position to cause said arms and sheaves to swing downwardly, means to cause the arms to release the sheaves in the last named position, means to raise the arms from the last named position, and means operated upon rising of 10 said arms to cause the return of said support and arms to the normal sheaf receiving position.

15. A stooking machine comprising a rotative support, a plate pivotally carried thereby, arms movably carried by said plate 20 to grasp sheaves, a latch normally holding said plate in operative position upon said support, means to cause the arms to close upon the contained sheaves, means to cause rotation of said support upon closing of 25 said arms to the sheaf delivering position, means to cause the latch to release the plate from the support in the last named position to permit the plate to swing down with the arms and sheaves, means to cause return 30 of said plate and arms to normal position respecting the support, and devices operated by said latch upon rising of said plate to cause the support to be rotated back to normal sheaf receiving position.

35. 16. A stooking machine comprising a turntable, a plate pivotally carried thereby, a latch to retain said plate in normal position upon the turntable, relatively movable arms carried by said plate, a stud connected 40 with said arms to operate the latter, a cam to coact with said stud, mechanism to actuate said cam, devices to rotate said turntable, clutch mechanism to control said devices, means actuated with said cam to operate 45 the clutch devices to cause the turntable to rotate to the sheaf depositing position upon closing of said arms, an arm 82 to coact with the latch to release said plate upon the turntable reaching the stook depositing 50 position, means to cause said arms to release the sheaves in the last named position, means to cause said plate and arms to rise from the sheaves, said latch being arranged to operate said arm 82 upon rising of said plate, 55 and means operated by said arm 82 to shift the clutch mechanism to cause said devices to rotate the turntable and arms together toward normal position.

17. A stooking machine comprising a 60 turntable, a plate movably carried thereby, a latch to normally hold the plate with respect to the turntable, arms movably carried by said plate to receive sheaves, mechanism to close said arms upon contained sheaves, 65 gearing to rotate said turntable, clutch

mechanism to control said gearing, an arm 72 operatively connected with said clutch mechanism, the turntable having means to normally hold said arm 72 to retain the clutch mechanism in a neutral position, devices connecting said arm 72 with the first named mechanism to cause said arm to shift the clutch mechanism upon closing of said sheaf grasping arms to cause the gearing to rotate the turntable to the sheaf depositing 75 position, said turntable having means to move said arm 72 to shift the clutch mechanism to neutral when the turntable reaches the last named position, an arm 82 having means to engage the latch to release said 80 plate to permit the sheaves and their arms to swing downwardly, means to return said plate and arms to the turntable, the arm 82 being in position to be engaged by the latch upon return of the plate to shift arm 82, 85 means to cause arm 82 to shift arm 72 upon the rise of said plate to shift the clutch mechanism to cause said gearing to return the turntable and sheaf arms to normal.

18. A stooking machine comprising a 90 turntable, sheaf receiving arms movably connected therewith, mechanism to cause said arms to close upon contained sheaves, said mechanism comprising clutch devices to cause operation thereof at will, a gear connected with the turntable, pinions meshing with said gear, a driving shaft for said pinions, a clutch body interposed between said pinions, clutch members on said pinions and body, a sleeve carrying said clutch body, an 95 arm 72 operatively connected with said sleeve, means on the turntable to coact with said arm to retain said clutch body in the neutral position between said pinions, means operatively connected with the first named 100 mechanism to move said arm 72 to shift said body to cause one of said pinions and said gear to rotate the turntable upon closing of said sheaf receiving arms, means upon the turntable to coact with said arm 72 to restore it to neutral when the turntable is in the sheaf depositing position, means to cause 105 said arms to deposit sheaves and release the arms therefrom, means connected with said arms to shift arm 72 and said clutch body 110 when the sheaf-holding arms return from depositing the sheaves to cause said gear and one of the pinions to rotate the turntable back to normal.

19. A stooking machine comprising a turntable, relatively movable arms carried by the turntable to receive sheaves, a stud, rods movably connecting the stud with said arms, a spring connected with said arms to spread them apart, a guide for said stud, a cam to 120 operate said stud, means to rotate said cam at will, mechanism to rotate the turntable to the sheaf depositing position, and means to cause said arms to deposit and release the contained sheaves. 125

20. A stooking machine comprising a turntable, a plate pivotally carried thereby, means for retaining the plate in operative position upon the turntable, arms movably carried by said plate to receive sheaves, a stud, rods movably connecting the stud with said arms, said plate having a guide for said stud, a spring connected with said arms to spread them apart, a cam to operate said stud, mechanism to operate said cam, clutch devices to control said mechanism at will, means to cause rotation of the turntable upon closing of said arms, means to release said plate from the turntable in the sheaf depositing position, means to cause said arms to release the sheaves, means to cause said arms to return upon the turntable to the sheaf receiving position, and means to cause the turntable to return with the arms 20 to the normal position.

21. A stooking machine comprising a frame, a sheaf receiver movably mounted thereon, a cam located below and adapted to actuate said receiver to cause the receiver to grasp sheaves, means to shift said sheaf receiver and frame relatively one to another from a sheaf receiving to a sheaf depositing position after the receiver has grasped the sheaves, and means to cause the receiver to 30 release sheaves in the last named position.

22. A stooking machine comprising a frame, relatively movable upwardly disposed arms movably supported upon said frame, an intermittently rotative cam below said 35 arms, means to cause said cam to close said arms upon sheaves before the receiver is shifted, means to shift said receiver from an upwardly disposed sheaf receiving position to a horizontally disposed sheaf depositing 40 position, and means to cause said arms to release the sheaves when in the last named position.

23. A stooking machine comprising a frame, a turntable rotatively and shiftably 45 mounted upon said frame, sheaf receiving arms carried by said turntable, means to cause said arms to close upon contained sheaves before the turntable rotates, means to cause said turntable and arms to rotate to 50 a sheaf depositing position, means to cause said turntable and frame to shift longitudinally one with respect to another, and means to cause the arms to release contained sheaves.

55 24. A stooking machine comprising a frame, a turntable pivotally and shiftably mounted thereon, upwardly disposed arms movably carried by the turntable to grasp sheaves and pivoted on the turntable to 60 swing vertically and outwardly away from the turntable, a projection connected with said arms, means to cause said turntable and frame to be shifted longitudinally one with respect to another, and an abutment carried 65 by said frame to coact with said projection

to cause said arms to release sheaves while the turntable is being shifted.

25. A stooking machine comprising a frame, a turntable, pivotally and shiftably mounted thereon, relatively movable arms carried by the turntable and normally projecting upwardly above the same, means to cause the arms to close upon contained sheaves, a projection connected with said arms, means to permit the arms to be swung 70 around a vertical axis with the turntable from a sheaf receiving to a sheaf depositing position, means to shift the turntable and frame longitudinally one with respect to another, and an abutment carried by the frame 75 to coact with said projection to spread the arms and release sheaves when the turntable is being shifted.

26. A stooking machine comprising a frame, a turntable pivotally and movably 80 mounted thereon, and a pair of normally upwardly extending arms to receive sheaves, means for supporting said arms upon and extending upwardly above the turntable to have downward and upward swinging movement relative to the turntable, means to retain the arms spread apart in an upward position to receive sheaves, means to release the arms from the turntable to swing downwardly while the turntable and arms are rotated to the sheaf depositing position, means to shift the turntable and frame longitudinally one with respect to another when the turntable is rotated to the sheaf depositing 90 position, an abutment upon the frame, and a projection connected with said arms to engage said abutment during shifting of said turntable to spread the arms apart to release sheaves.

27. A stooking machine comprising a frame, a slide movably mounted thereon, a turntable carried by the slide, upwardly disposed sheaf receiving arms pivotally carried by the turntable, means to close the arms upon contained sheaves, means to rotate the 105 turntable and arms upon said slide, means to release the arms to swing downwardly when the turntable reaches the limit of its rotation, means to cause the slide to shift back and forth upon the frame intermittently, and means to cause the arms to open and release sheaves when the turntable has 110 been shifted rearwardly of the frame and to restore the arms to the open upward position upon the turntable after depositing the 115 sheaves.

28. A stooking machine comprising a frame, a slide mounted thereon for shifting in the direction of travel of the machine, a turntable rotatively mounted upon the slide, 120 normally spread upwardly disposed sheaf-receiving arms carried pivotally by the turntable to swing downwardly away from the turntable, means to cause the arms to grasp contained sheaves, means to cause the turn- 125

- table to rotate substantially one-half revolution upon the slide with the arms closed upon sheaves, means to permit the arms to swing down and deposit contained sheaves
- 5 upon completion of one-half rotation of the turntable, means to shift the slide and turntable upon the frame in a direction reverse to the direction of travel of the frame, means to cause the arms to spread and release 10 sheaves in the last named position, and means to restore the spread arms and turntable to the normal sheaf receiving position.
29. A stooking machine comprising a frame, a slide movable thereon, a turntable 15 carried by said slide, a plate movably carried by said turntable, means to lock the plate to the turntable, sheaf receiving arms carried by the plate, means to cause the arms to grasp contained sheaves, means to cause 20 the plate and arms to revolve bodily around and release the plate from the turntable to cause the plate and arms to swing downwardly to the sheaf depositing position, mechanism to shift said slide and turntable 25 rearwardly of the machine, means to cause the arms to spread apart when swung down to release contained sheaves during shifting of said slide, means to cause said plate and the spread arms to return to sheaf receiving 30 position, and means to return the turntable to normal sheaf receiving position upon said frame.
30. A stooking machine comprising a frame, a turntable pivotally and shiftably 35 mounted thereon, upwardly disposed sheaf receiving arms pivotally carried by the turntable, means to cause said arms to grasp contained sheaves, means to release the arms to swing downwardly when the turntable 40 reaches the limit of its rotation, means to rotate the turntable, means to shift the turntable rearwardly of the frame, and mechanism connected with the turntable to release

said shifting means, and a spring to restore the turntable to its normal position on the 45 frame.

31. A stooking machine comprising a frame, a slide carried thereby, a turntable pivotally mounted on the slide, sheaf receiving arms carried by the turntable, means to 50 lock the arms to the turntable, a cam beneath the arms to cause said arms to grasp contained sheaves, a rack connected with the slide, a gear to actuate the rack, means to rotate said gear, clutch mechanism to control 55 rotation of said gear, means connected with the turntable to cause the clutch mechanism to operate the gear, means to release the arms from the turntable to swing downwardly and means to cause said arms to release contained sheaves when the slide is shifted by said gear.

32. A stooking machine comprising a frame, a slide mounted thereon, a turntable pivotally carried by the slide, sheaf receiving arms carried by the turntable, means to lock the arms to the turntable, a cam beneath the arms to cause the arms to grasp contained sheaves, means to cause the turntable to rotate to the sheaf depositing position, gearing to operate said slide, a wheel connected with said frame, transmission mechanism from said wheel to said gearing, a clutch to connect the gearing with said transmission mechanism, means connected 70 with the turntable to operate said clutch and means to release the arms from the turntable to swing downwardly.

Signed at New York city, in the county of New York and State of New York, this 27th 80 day of April, A. D. 1912.
